UNITED STATES PATENT OFFICE.

ALFRED STROMBERG, OF CHICAGO, ILLINOIS.

TELEPHONE-EXCHANGE SYSTEM AND APPARATUS.

SPECIFICATION forming part of Letters Patent No. 662,986, dated December 4, 1900.

Application filed June 6, 1900. Serial No. 19,287. (No model.)

To all whom it may concern:

Be it known that I, ALFRED STROMBERG, a citizen of the United States, residing at Chicago, in the county of Cook and State of Illinois, have invented a certain new and useful Improvement in Telephone - Exchange Systems and Apparatus, (Case No. 7,) of which the following is a full, clear, concise, and exact description, reference being had to the accompanying drawings, forming a part of this specification.

My invention relates to telephone-exchange systems and apparatus, and has for its object the provision of an improved construction of switchboards involving an improved form and arrangement of spring-jacks, whereby a much larger number of spring-jack switches may be assembled upon each section of board.

The invention further contemplates an improved circuit arrangement of the operator's apparatus and of the telephone-lines and line apparatus at the exchange, whereby the number of switches may be reduced to a minimum, and whereby single-stranded-cord sets may be employed in completing connection between subscribers of metallic circuit-lines. Heretofore two general forms and arrangements of spring-jacks have been employed. In one form and arrangement a vertically-arranged board provided with holes faced with metal bushings designed to receive connecting-plugs has been commonly employed, the switch-springs of the spring-jacks being disposed to the rear of the metal bushings or thimbles in position to be engaged by inserted plugs, the switch-springs being mounted upon individual horizontally-disposed strips of insulating material mounted directly upon the rear of the aforesaid vertical board. In early telephone practice this construction was adequate; but when the number of lines in a given exchange became vastly increased this construction of the prior art was insufficient to accommodate the increased number of multiple spring-jacks that should be provided upon each section of the switchboard. This structure of the prior art failed in this respect because of the great space required for the horizontally-arranged spring supporting strips.

Another arrangement and construction of the prior art consisted in the vertical board

and individually-complete spring-jacks having metallic frames provided with thimble plug-receiving extensions inserted from the rear of the said vertical board in holes provided therein. This construction is also objectionable in that the metallic frames of the individually-complete jacks occupy considerable space both horizontally and vertically.

In accordance with my invention I dispense with all horizontally-extending frames or supports for the springs and provide in place thereof a vertical support, which affords a mounting for a plurality of horizontal rows of springs, which may be closely assembled vertically and horizontally, as this vertical support serves to merely anchor the springs in place. These springs constitute line connections of spring-jacks, a second vertical support being employed that constitutes the face of the switchboard-section, this second vertical support containing metallic test-thimbles in the case of multiple boards from which metallic strips are extended toward the rear and anchored also at their rear ends in the same vertical support that carries the springs, these metallic strips acting as electrical connections for the test-thimbles and also serving to unite the two vertical supporting members to maintain the proper distance between the same to secure proper alignment of the thimbles with relation to the switch-springs of the multiple jacks and to form a firm integral structure.

By means of my invention I am enabled to employ a single line-spring in each spring-jack, whereby the construction is further simplified. Heretofore each operator has been provided usually with not more than five thousand line-jacks upon her section of multiple board. I have been enabled by means of my invention to provide each operator's section of multiple board with about four times as many line spring-jacks, so that the capacity of the exchange may be greatly increased without enlarging the space required for the apparatus.

I will describe my invention and additional details fully by referring to the accompanying drawings, illustrating the preferred embodiment thereof, in which—

Figure 1 is a front elevation of a switchboard constructed in accordance with my in-

vention. Fig. 2 is a plan view of a bank of spring-jacks, parts being shown in section more clearly to reveal features of construction. Fig. 3 is a front view of a portion of the structure shown in Fig. 2. Fig. 4 is a side view of the structure illustrated in Fig. 2, parts being broken away to reveal features of construction. Fig. 5 is a diagrammatic view illustrating a subscriber's station connected with a multiple switchboard; and Fig. 6 is a rear view of a thimble, showing the manner of securing a conductor thereto.

I preferably assemble the spring-jacks in banks, each bank constituting a unit, the banks being preferably arranged in vertical panels, three panels arranged side by side preferably constituting a section of the board. In practice I have been enabled to arrange the jacks a fourth of an inch apart between centers both vertically and horizontally, and I prefer to assemble one hundred of these jacks in each bank, five rows of twenty jacks each being preferably contained in each bank. The front face or support A of insulating material of each bank contains the test-thimbles B, arranged in parallel rows. These test-thimbles are provided with continuous rims at their front ends and with serrated rims at their rear ends. The teeth C' of the rear rims, Fig. 6, by being bent into engagement with the ring ends of the strip conductors C serve to mechanically and electrically unite the conductors C with the thimbles. A second vertical support D is provided to the rear of the face A, the strip conductors C serving as distance-pieces to maintain the proper space between the supports A and D. In order that the conductors C may best serve this function, I provide the same with grooves C² at their rear ends, as indicated clearly in Fig. 4, these grooves being of a length corresponding to the width of the support D, whereby said support by snugly fitting the said groove is prevented from having motion toward or from the support A. With the supports A and D thus relatively fixed the line-springs E may be secured to the support D and held in proper position with relation to the thimbles. In order that the line-springs may be properly held in place, I also provide the rear or anchored ends thereof with grooves E', corresponding in length to the width of the support D. I preferably form the front support A of each bank in one integral piece of fiber, while the rear support D is preferably formed of as many horizontal strips of fiber as there are rows of jacks in each bank, these strips of fiber being preferably provided with saw-cuts in which the strips C and springs are received, the groove portions of the strips and springs preventing the longitudinal displacement of the springs and strips C with respect to the support D, while the saw-cuts prevent their lateral displacement. The spring-jacks are thus built in banks, which may be assembled vertically to form panels, as indicated in Fig. 1.

An important feature of my invention consists in the provision of improved means for wiring boards constructed as described, which feature may also be employed in connection with boards of other construction. Instead of providing the rear ends of the conductors C and E with holders for attachment of wire, the practice hitherto generally followed, I provide the said ends with an open recess C² in an edge of each of these conducting portions. By this means I am enabled to pass the line and test conductors back of the multiple-switchboard sections and to effect connections thereof with the conductors C and E without cutting the wire, but by merely forming loops G therein, the insulation being scraped away from the wire where it is to be soldered to the conductor, the loops being extended forwardly from the conductors. I thus provide a very simple and effective way of wiring the board without introducing a great number of joints or soldered connections as component parts of the conductors.

I preferably employ the system illustrated diagrammatically in Fig. 5, where I have illustrated a well-known form of telephone appliance, comprising a telephone-receiver H, transmitter I, together with the primary and secondary coils, a signal-bell K, and switchboard L. This telephone-station is connected by means of metallic circuit M N with the several sections of the multiple board. The limbs N of each telephone-line extending along the board are preferably directly united at a common point, with which a pole of the common battery O is connected. The other pole of the common battery is shown as connected to the cord-strand P, provided with terminal plugs Q Q, a clearing-out drop R being included in the conductor connecting the common battery with the cord-strand. I have not indicated the line-indicator in connection with the metallic circuit M N, as this forms no part of the present invention.

I have illustrated an answering-jack S, in which the answering-plug may be inserted. By the arrangement shown a single line-spring at each line-jack is only required; but in order that induction and cross-talk may be avoided the conductor M is provided with loops T, that extend parallel with the loops G, whereby this induction is counteracted. The loops G and T are preferably twisted, more effectively to secure the desired result. I have indicated the loops G and T as being distinct, but they may be interwound if desired.

There are features of my invention that are capable of use in other systems than multiple-switchboard systems, particularly the manner of connecting the line conductors with the line-springs.

I have herein shown and particularly described the preferred embodiment of my invention, but I do not wish to be limited to the precise embodiment of the invention dis-

closed, as modifications may be made without departing from the spirit thereof; but,

Having thus described my invention, I claim as new and desire to secure by Letters

5 Patent—

1. In a telephone - exchange system, the combination with the limbs of a metallic-circuit telephone-line, of a line-switch provided on a switchboard, one limb of the line being 10 provided with a loop at said line-switch, which is connected with the said switch, the other limb of the line being also provided with a loop at said line-switch, but free of direct connection with said line-switch, substantially as described.

15 2. In a telephone - exchange system, the combination with the limbs of a metallic-circuit telephone-line, of a plurality of line-switches provided on a switchboard, one limb 20 of each line being provided with a loop at, and connected with, each of said line-switches, the other limb of the line being also provided with a loop at each line-switch, but free of direct connection therewith, the said loops being 25 substantially as described.

3. In a telephone - exchange system, the combination with a plurality of metallic telephone-lines extending to and from the exchange, one limb of each of the metallic telephone-lines being connected directly together 30 at the exchange, independently of cord connecting apparatus, of a single cord-strand provided with suitable connecting means adapted to connect the remaining limbs of the metallic-circuit telephone-lines, a telephonic circuit 35 between the subscribers thereby comprising the limbs of the metallic lines that are directly connected at the exchange, and the single cord-strand with the remaining limbs 40 united thereby, a common battery connected in bridge at the exchange between the cord-strand and the directly-united limbs of the telephone-lines, and an indicator in the same bridge with the battery; the limbs of the telephone-lines that are not permanently connected being each provided with a loop extending to and connected with a line-switch at the exchange, the directly-connected limbs 45 of the line being also provided with a loop extending parallel with the loop that is connected with the switch to avoid induction, substantially as described.

4. In a telephone - exchange system, the combination with a plurality of metallic telephone-lines extending to and from the exchange, one limb of each of the metallic telephone-lines being connected directly together 55 at the exchange, independently of cord connecting apparatus, of a single cord-strand provided with suitable connecting means adapted to connect the remaining limbs of the metallic-circuit telephone-lines, a telephone-circuit 60 between the subscribers thereby comprising the limbs of the metallic lines that are directly connected at the exchange, and the single cord-strand with the remaining limbs 65

united thereby, a common battery connected in bridge at the exchange between the cord-strand and the directly-united limbs of the telephone-lines, and an indicator in the same 70 bridge with the battery; the limbs of the telephone-lines that are not permanently connected being each provided with a loop extending to and connected with a line-switch at the exchange, the directly-connected limbs 75 of the line being also provided with a loop extending parallel with the loop that is connected with the switch to avoid induction, the said loops being twisted, substantially as described.

5. In a telephone - exchange system, the combination with a plurality of metallic telephone-lines extending to and from the exchange, one limb of each of the metallic telephone-lines being connected directly together 80 at the exchange, independently of cord connecting apparatus, of a single cord-strand provided with suitable connecting means adapted to connect the remaining limbs of the metallic-circuit telephone-lines, a telephonic circuit 85 between the subscribers thereby comprising the limbs of the metallic lines that are directly connected at the exchange, and the single cord-strand with the remaining limbs 90 united thereby, a common battery connected with the directly-united limbs of the metallic lines, and with the cord-strand and an indicator in the circuit with the battery and cord-strand; the limbs of the telephone-lines being each provided with a loop, a switch 100 connected with one of the loops of each line, the companion loop of the directly-connected limb extending parallel with the aforesaid loop that is connected with the switch to avoid induction, the said loops being twisted, substantially as described.

6. In a telephone - exchange system, the combination with a plurality of telephone-lines extending from subscribers' stations to an exchange, one limb of each of the lines being permanently connected together at the exchange independently of cord connecting apparatus, of a single cord-strand provided with a single connecting means adapted to connect the remaining limbs of the lines, the 110 telephonic circuit between the subscribers thereby comprising the limbs of the lines that are directly connected at the exchange and the single cord-strand with the remaining limbs 115 united thereby, and line-switches connected with limbs that are connected through the agency of the cord-strand, the limbs of the lines extending along the switchboard, the said limbs being provided with parallel loops, the loops of the permanently-united 120 limbs being free of direct connection with the line-switches, while the loops of the remaining limbs have direct connection with the line-switches, the said loops coöperating to prevent cross-talk, substantially as described.

7. In a switchboard, the combination with a front vertical support formed in one inte-

gral piece provided with a plurality of horizontal rows of plug-openings, of a rear vertical support united to the aforesaid support, and a plurality of rows of line-springs mounted in the rear vertical support contiguous to the said openings, whereby the plug-openings may be brought closer together vertically as well as horizontally, substantially as described.

10. 8. In a multiple switchboard, the combination with a front vertical support formed in one integral piece provided with a plurality of horizontal rows of test-thimbles, of a rear vertical support, a plurality of rows of line-springs mounted in the rear vertical support contiguous to the said thimbles, and conductors C attached to the test-thimbles and engaging the rear vertical support, whereby the said conductors C act to unite the vertical supports and at the same time convey current to the test-thimbles, substantially as described.

15. 9. In a multiple switchboard, the combination with a front vertical support provided with a plurality of horizontal rows of test-thimbles, of a rear vertical support, a plurality of rows of line-springs mounted in the rear vertical support contiguous to the said thimbles, and conductors C attached to the test-thimbles and engaging the rear vertical support, whereby the said conductors C act to unite the vertical supports and at the same time convey current to the test-thimbles, substantially as described.

20. 10. In a multiple switchboard, the combination with a front vertical support provided with a plurality of horizontal rows of test-thimbles, of a rear vertical support, a plurality of rows of line-springs mounted in the rear vertical support contiguous to the said thimbles, and conductors C attached to the test-thimbles and engaging the rear vertical support, whereby the said conductors C act to unite the vertical supports and at the same time convey current to the test-thimbles, substantially as described.

25. 11. In a multiple switchboard, the combination with a front vertical support provided with a plurality of horizontal rows of test-thimbles, of a rear vertical support, a plurality of rows of line-springs mounted in the rear vertical support contiguous to the said thimbles, and conductors C attached to the test-thimbles and engaging the rear vertical support, whereby the said conductors C act to unite the vertical supports and at the same time convey current to the test-thimbles, substantially as described.

30. In witness whereof I hereunto subscribe my name this 14th day of May, A. D. 1900.

ALFRED STROMBERG.
